* cited by examiner

(73) Assignee: **Progressive International Corporation**, Kent, WA (US)

Primary Examiner—Terry A Wallace

(74) *Attorney, Agent, or Firm*—Black Lowe & Graham, PLLC

(**) Term: **14 Years**

(57) **CLAIM**

(21) Appl. No.: **29/330,234**

I claim the ornamental design for the collapsible salad spinner strainer basket, as shown and described.

(22) Filed: **Dec. 31, 2008**

DESCRIPTION

(51) **LOC (9) Cl.** 07-04

FIG. 1 is a perspective view of the collapsible salad spinner strainer basket, showing my new design;

(52) **U.S. Cl.** D7/667

FIG. 2 is a front view of the collapsible salad spinner strainer basket, the back, left side, and right side views being identical;

(58) **Field of Classification Search** D7/665–668,

FIG. 3 is a top view of the collapsible salad spinner strainer basket;

D7/601, 602, 629, 538–542, 400; 210/464,

210/465, 470–478, 498, 499; 99/455, 501–513;

220/574–575, 780–806; D32/55;

See application file for complete search history.

FIG. 4 is a bottom view of the collapsible salad spinner strainer basket; and,

(56) **References Cited**

FIG. 5 is an exploded view of the collapsible salad spinner strainer basket, shown together with a representative lid and bowl in which the lid and bowl are shown in phantom and form no part of the claimed invention.
